INVENTOR.

Margaret Evelyn Waples
BY
Wm. Hubbell Fisher
ATTORNEY.

UNITED STATES PATENT OFFICE.

MARGARET EVELYN WAPLES, OF ANN ARBOR, MICHIGAN.

HAT-FASTENER.

SPECIFICATION forming part of Letters Patent No. 703,507, dated July 1, 1902.

Application filed July 19, 1900. Serial No. 24,209. (No model.)

To all whom it may concern:

Be it known that I, MARGARET EVELYN WAPLES, a citizen of the United States, and a resident of the city of Ann Arbor, in the 5 county of Washtenaw and State of Michigan, have invented certain new and useful Improvements in Hat Shields and Fasteners for Hat-Pins, of which the following is a specification.

10 One of the objects of my invention is to provide a device which when attached to the hat shall securely hold the hat-pin in place therein.

Another object of my invention is to provide a device that shall shield the hat from 15 those thrusts of the sharp point of the hat-pin which are usually made in attempting to put the hat-pin in position and shall confine the hat-pin to one fine opening through the hat, thereby saving the hat from numerous 20 destructive and ugly punctures.

Another object of my invention is to provide a device which can be located on one side only of the hat and shall not pass through the hat nor thus or in any other manner injure it.

25 Another object of my invention is to provide a shield with such elasticity and softness of material that the point of the hat-pin when impinging against it cannot be injured.

Another object of my invention is to combine with a shield and fastener containing 30 one or more features of my invention a series of guides for aiding the wearer to find the hole in the fastener with the point of the hat-pin after the pin has been passed through 35 the hair.

Among the other objects to be secured by my invention are simplicity of construction, economy of manufacture, ease of attachment and of manipulation, and durability.

40 The several features of my invention and the various advantages resulting from their use conjointly or otherwise will be apparent from the following description and claims.

In the accompanying drawings, making a 45 part of this application, and in which similar letters of reference indicate corresponding parts, Figure 1 represents an elevation of the front of a device, illustrating my invention. Fig. 2 represents an elevation of the rear of 50 the device. Fig. 3 is a vertical transverse section of the same, taken at the plane of the

dotted line 3 3 of Fig. 1. Fig. 4 shows in perspective a disk of sponge-rubber which is contained between the disks of my device. Fig. 5 represents an elevation of the front of my 55 device when modified by the omission of the front radial guides.

I will now proceed to describe my invention in detail.

I select a material that is elastic or semi- 60 elastic and not so hard as to injure the point of the hat-pin impinging against it. A desirable material containing these requisites is celluloid. I employ two pieces (respectively marked A and A²) of such material. 65 These pieces are preferably discal in form, but may be angulated in outline. Each of these pieces has a small central aperture B, which extends through it. Between these pieces is located a small piece C, of sponge- 70 rubber or equivalent elastic material, concentric with the passage B. This piece C is somewhat compressed between the pieces A and A². The compression of the rubber causes it to fill not only the aperture B in the 75 front and back piece A², but to project outwardly beyond it. This projection C² will arrest the point of the needle as it is moved over the plate A. Thereupon the point of the pin can be pressed through the rubber. The 80 pieces A and A² are suitably secured together, usually near their periphery. The preferred means for thus uniting them are the eyelets D, each of which is passed through a hole in each of the pieces A and A² and clamped or 85 fastened in position. This junction of the two pieces by means of the eyelets will bring the edges of these pieces closer together than the sponge-rubber C allows their middle portions to approach each other, and thus the 90 rubber is compressed between them and held firmly in position.

To the more readily guide the point of the hat-pin to the aperture B, I provide the front or outer face of the piece A with radial guides 95 E, which latter extend from or near the periphery of the piece to the aperture B. These radial guides may consist of recesses or projections or ribs. In the drawings I have illustrated the latter form of construction.

100 The device as an entirety is to be sewed or otherwise fastened to the inside or outside of

the hat in that part of the hat where the wearer desires to use the hat-pin, and it may be directly attached to the hat itself or the lining or bands, &c., thereof, either alone or 5 in combination with or as a part of any ornament or useful device, such as a buckle or rosette.

Where the eyelets D are present, they serve as a convenient means for securing the device 10 to the hat by sewing.

The guides E become of importance when the device is secured on the inside of the hat.

After passing the hat-pin through the hair with its point directed toward the shield the 15 said point will strike some part of the shield's surface. It is then an easy matter to move the head of the pin slightly, so as to cause the point to reach some one of the guides and follow it to the aperture B. The elastic sub-20 stance there at once holds the point, which is readily pushed through it. When the hat is to be removed, the pin is readily withdrawn.

A device thus made according to my invention 25 obviously secures the objects stated in the opening of my specification.

In certain instances the guides E may be omitted. (See Fig. 5.)

What I claim as new and of my invention, 30 and desire to secure by Letters Patent, is—

1. A plate, having a central aperture, radial guides combined therewith, a rubber against the back of said plate, and means adapted to hold the rubber in place at the 35 back of said plate, the rubber compressed between such plate and said rear holding means, and extending through the said aperture,

substantially as and for the purposes specified.

2. A hat-pin, guide, shield and fastener composed of two pieces A and A² having a central aperture, and an elastic medium located between these, covering these apertures, and extending beyond their edges, and confined between these pieces so as to extend through 45 the apertures, thus presenting a raised surface, adapted to catch the point of the pin, substantially as and for the purposes specified.

3. A hat-pin, guide, shield and fastener composed of two pieces A and A² having a central aperture, and an elastic medium located between them, covering these apertures, and extending beyond their edges, and confined between these pieces so as to extend through 55 the apertures, thus presenting a raised surface, adapted to catch the point of the pin, and the piece having the radial ribs, substantially as and for the purposes specified.

4. As an article of manufacture, two flat 60 discal plates, of metal or the like, each having a central aperture, and so located with reference to each other that these apertures are concentric, a discal diaphragmic piece of rubber located between these two plates, and 65 across the aperture of the plates, and in connection with the inner plate, radial ribs leading from the outer or circumferential edge of the plate to the central aperture, substantially as and for the purposes specified.

MARGARET EVELYN WAPLES.
